BOX OR CARTON

Thomas B. Schmidt, Harrisburg, Pa.

Application May 4, 1933. Serial No. 669,431

1 Claim. (Cl. 206—44)

This invention relates to improvements in boxes or cartons, and more particularly to a combined shipping and display container for articles such as cakes and the like.

5 The primary object of the invention is to provide a box of cardboard or the like, the base section of which is shallower than the other section so that a substantial portion of the contents of the box may be displayed when the cover section 10 is removed; said shallow section being combined with a reinforcing or supporting stand which prevents undue movement or crushing of the box and its contents during transportation.

A further object is to provide a stand or frame 15 for boxes of this character which is sufficiently rigid to permit stacking a number of such boxes in superposed relation without damaging the boxes or their contents.

With the foregoing objects outlined and with 20 other objects in view which will appear as the description proceeds, the invention consists in the novel features hereinafter described in detail, illustrated in the accompanying drawing, and more particularly pointed out in the appended 25 ed. claim.

In the drawing,

Fig. 1 is a perspective view of the improved box or carton.

Fig. 2 is a similar view with the cover or deep 30 section of the box in a position above the base section and reinforcing stand.

Fig. 3 is an enlarged vertical sectional view of a detail partly in elevation, taken on the line 3—3 of Fig. 1.

35 Fig. 4 is a view similar to Fig. 3, but taken on the line 4—4 of Fig. 1.

Referring to the drawing, 5 designates my improved box or carton, preferably made of suitable sheet material, and of rectangular form, although 40 it is obvious that such boxes may be of other shapes.

My invention consists essentially of three elements, namely, a deep or cover portion 6, a shallow or base portion 7, and a wire frame or 45 support 8.

The cover 6 and base 7 may each be made from a blank of cardboard or the like, folded in the manner indicated at 9 and 10 respectively, and the folded edges of the respective portions 6 and 7 50 may be glued or stapled in any suitable manner to form cover and bottom portions which will coact when assembled to form a box or carton for transporting or displaying a cake 11 or the like which may be wrapped in "Cellophane" 11a or 55 other suitable material, as indicated in Figs. 3

and 4. At this point it will be noted that the side walls 12 of the cover 6 are of greater height than the side walls 13 of the bottom 7.

The wire frame or support 8 which may be arranged within the box, consists of a one-piece 60 wire element bent to form a pair of spaced parallel longitudinal bars 14 which are adapted to rest on the bottom 15 of the base of the box. Uprights 16 extend from the ends of said bars 14 and support at their upper ends, a pair of transverse parallel supporting bars 17 arranged substantially at right angles to the bars 14. The ends of the one-piece wire element may be welded or otherwise suitably connected together. As may be seen from the drawing, the uprights 14 are 70 of a height approximately equal to the height of the cover 6, so that when the cover is placed over the base of the box, the bottom surface of the cover will rest on the transverse bars 17 and thereby be prevented from crushing the box contents. Furthermore, with a box and support of this 75 character, it will be possible to stack a number of such boxes in superposed relationship without danger of crushing or damaging the boxes or their contents.

In order to further protect the cake or the like, I provide a false bottom 19 which may comprise a sheet of relatively stiff material such as cardboard or the like. The false bottom is arranged within the base 7, and rests on the horizontal 80 bars 14.

The false bottom 19 provides a flat surface upon which the cake may rest, and prevents moisture or dampness in the cake from penetrating the bottom 15 of the box and thereby damaging the same. Moreover, the false bottom 19 prevents the bottom of the cake from being damaged by the 85 bars 14.

From the foregoing description it will be apparent that my improved box and supporting 90 frame will provide a neat and attractive display device for cakes and the like. Ordinarily, in displaying articles of this character, the cake is either removed from the box or has to remain within a relatively deep bottom section of such a 95 box. As the result, when the cake is taken out of the box and placed on the counter for display purposes, it is liable to be damaged or bruised when other articles are placed on top of the same, or when the cake is pushed or moved against other objects on that counter. On the other hand, if the cake is left within the box and the cover is removed, only the top portion of the 100 cake will be visible. The average iced cake often presents a very serious problem to bakers, for the 105 110

reason that the transparent paper wrapper is frequently pressed into the cake and sticks to the same so that, in unwrapping the cake, much of the icing sticks to the paper. This not only mars the appearance of the cake but results in a loss of much of the icing. Furthermore, this unsightly condition of the cake is apparent to a prospective purchaser and often results in the loss of a sale.

10 The above objections are eliminated by means of the present invention, since it is evident that with a box and support of the character described, substantially the entire cake is displayed without removing the same from the shallow or base portion 7. Furthermore, the support or frame 8 prevents the cake from being damaged when other objects are pushed or moved into contact therewith. Moreover, due to the special construction of the frame 8, cakes may be stacked 15 in superposed relation with or without the cover thereon, as the bottom surface of the upper box 20 will rest on the transverse supporting bars 17 of the frame in the lower box.

While I have disclosed what I now consider to

be a preferred embodiment of the invention in such manner that the same may be readily understood by those skilled in the art, I am aware that changes may be made in the details disclosed, without departing from the spirit of the invention, as expressed in the claim. 80

What I claim and desire to secure by Letters Patent is:

A container for a layer cake or the like, comprising a base portion having a relatively short upstanding annular wall of uniform height, a reinforcing frame having lower members resting on the bottom of said base, rigid upstanding members forming part of the frame and projecting upwardly above said wall, upper members horizontally arranged and supported by the upper ends of the upstanding members, a relatively stiff false bottom resting on said lower members and forming a support for a cake or the like, and a relatively deep cover portion resting on the upper members of the frame and having a depending annular skirt overlapping said annular wall. 85 90 95
